(57) **CLAIM**

The ornamental design for a dog walking belt bag as shown and described.

DESCRIPTION

FIG. 1 is a top, left front perspective view of a dog walking belt bag showing my new design, with the dog walking belt bag in a first unbuckled configuration;

FIG. 2 is a back view thereof, with the dog walking belt bag in a second unbuckled configuration;

FIG. 3 is a front view thereof;

FIG. 4 is a top view thereof in the first unbuckled configuration;

FIG. 5 is a top, side perspective view thereof, with the dog walking belt bag shown in a buckled configuration;

FIG. 6 is a top view thereof;

FIG. 7 is a back perspective view thereof; and,

FIG. 8 is a back perspective view thereof, with the dog walking belt bag shown in a partially buckled configuration.
